MASS SPECTROMETER

George H. Lee, Oak Ridge, Tenn., assignor to the
United States of America as represented by the
United States Atomic Energy Commission

Application April 22, 1947, Serial No. 743,115

9 Claims. (Cl. 250—41.9)

1

My invention relates to isotope separating equipment, and more particularly to mass spectrometers employing alternating electrostatic fields for the separation of isotopes of elements.

In the prior art of isotope separation it has generally been the practice to heat a charge of material until it vaporizes, lead the vapors to an ionizing chamber, subject the neutral vapors to electron bombardment therein to ionize them, eject the ions from the ionizing chamber with accelerating potentials to bring them into the region of a magnetic field where they are caused to travel in arcuate paths of radii corresponding to their masses, and finally to collect the respective ions at or near the focal points of the ion beams. The structure and framework for setting up the magnetic field is generally bulky and cumbersome, and careful precautions must be taken to provide a uniform magnetic field to insure proper operation. The measurement, maintenance, and reproduction of a constant and homogeneous magnetic field is, therefore, often difficult and impractical.

Some efforts have been made in the prior art to provide a mass spectrometer employing an electrostatic field, set up by a high frequency alternating current, at right angles to the ion beam, instead of using a magnetic field. Without changing the frequency of the alternating current source and by utilizing harmonics of the same frequency, it is possible to improve accuracy in the separation, collection, or comparison of certain isotopes without introducing cumulative errors, since frequencies of the harmonics of an electric circuit are exact multiples of the fundamental to a high order of precision, and different harmonics may be employed to deflect ions of different mass. Examples of these efforts are set forth in *Physical Review*, vol. 28, pages 1275 to 1286, and *Physical Review*, vol. 40, pages 429 to 433. These systems, however, do not contemplate any arrangement for increasing the angular deflection of the displaced ions and in the case of heavy ions would require considerable spacing between the electrostatic field and the receivers to obtain the necessary displacement. Also, under these latter arrangements relying on alternating current deflecting fields, the angularly displaced ion beams will sweep back and forth across the receiver for the desired isotope and cause contamination, and the sweep of these ion beams back and forth across such receiver makes separation and collection of the sweeping beams into separate receivers impractical.

2

Applicant with a knowledge of these defects in and objections to the prior art has for an object of his invention the provision of isotope separating equipment with an alternating electrostatic field wherein the deflected ions are subjected to increased angular deflection to facilitate their separation and/or collection and to reduce the lengths of the paths of travel of the ions from the field to the collector.

10 Applicant has as another object of his invention the provision of an alternating electrostatic field mass spectrometer employing out of phase alternating currents to produce a rotating field so that a plurality of different isotopes may each be collected in spaced concentric circular receivers, or receivers forming sectors of circles of radii corresponding to their respective masses.

15 Applicant has as another object of his invention the provision of an alternating electrostatic field mass spectrometer employing alternating current potentials whereby selected isotopes of elements may be chosen for deflection and measurement and undesirable isotopes may pass therethrough substantially undeflected.

20 Applicant has as a further object of his invention the provision of an alternating electrostatic field mass spectrometer which produces alternating current pulses on the collectors when spaced sectors set in a plurality of circular tracks with radii corresponding to the respective masses of the isotopes to be measured, are employed.

25 Applicant has as a further object of his invention the provision of a mass spectrometer which produces alternating currents at the collectors and provides through amplification and conversion more accurate measurement of the isotopes collected.

30 Applicant has as a still further object of his invention the provision of a mass spectrometer which is particularly well adapted to the separation and analysis of isotopes of elements of the lower mass numbers.

35 Applicant has as a still further object of his invention the provision of an alternating electrostatic field mass spectrometer for selecting a desired isotope of a predetermined mass and causing it to travel undeflected to a collector or receiver.

40 Other objects and advantages of my invention will appear from the following specification and the accompanying drawings, and the novel features thereof will be particularly pointed out in the annexed claims.

45 In the drawings, Fig. 1 is a schematic of one arrangement of my improved mass spectrometer,

Fig. 2 is a schematic of the ion beam deflection arrangement for a modified form of my improved mass spectrometer. Fig. 3 is a schematic of a portion of my improved spectrometer employing the arrangement of Fig. 2. Fig. 4 is a schematic of the ion sectors and the circuit for making alternating current measurements of isotope currents. Fig. 5 is a schematic of another modification of the arrangement for deflecting the ion beams.

Referring to the drawings in detail, 1 designates a positive ion source of any conventional type such as is well known to the mass spectrometer art, wherein a suitable charge is vaporized by heating, and the vapors therefrom are fed to an ionizing chamber provided with an exit slit. In this chamber they are subjected to electron bombardment and are ionized by a stream of electrons emitted from a cathode and directed across the chamber. The ion source 1 is preferably maintained at high potential, such as 27.5 kv., from a suitable direct current source, indicated at 9. Positioned beyond the source 1 are spaced sets of accelerating electrodes 2, 2 having aligned slots which are in turn aligned with the exit slit in the ion source. These accelerating electrodes are preferably joined together electrically and grounded in order to maintain the ion beam at a high constant horizontal velocity during its passage between plates 3, 3 which are interposed between the electrodes 2, 2 and maintain a vertical alternating electrostatic field therebetween. Plates 3, 3 are fed from the ends of the centrally tapped secondary of transformer 4 with an alternating current voltage having a maximum value of, for example, 27.5 kv., delivered by any suitable alternating current source. The center tap of the secondary winding is grounded. The frequency of about 6 megacycles applied across plates 3, 3 is chosen so that the transit time through the plates 3, 3 for the desired ions, such as uranium 235, is exactly equal to the period or a multiple thereof, preferably one complete cycle of the alternating current applied to such plates.

Positioned beyond the accelerating electrodes 2, 2 is a decelerating electrode 5 having a slot therein aligned with the slots of the accelerating electrodes. The decelerating electrode 5 may be maintained at a high potential of about 27,225 volts from source 9 and this potential is only slightly less than that of the positive ion source 1. Positioned on beyond the decelerating electrode 5 and separated therefrom by space 6 is a screen 7 having a collector or receiver 8 which is in substantial axial alignment with the slots in the electrodes. The screen and collector are electrically connected to and maintained at substantially the same potential as the decelerating electrode 5. Ammeter 15 serves to measure the current resulting from the total ion collection on the screen and collector and neutralization thereof. Of course, the collector could be insulated from the screen and have a separate metered return lead to the supply, if desired, whereby the U-235 ion current could be separately measured.

In its operation a charge containing the isotopes to be separated is vaporized and the vapors ionized in source 1. The accelerating electrodes 2, 2 eject the ions from the exit slit in the source 1 and move them towards the screen 7 through plates 3, 3. Where the frequency of the alternating current potential applied to plates 3, 3 is so chosen that the transit time therethrough of the 235 uranium ion is equal to one period or

a multiple thereof, the integral of the vertical acceleration of the 235 ions during their passage through such plates is, therefore, equal to zero. Accordingly, all uranium 235 ions emerge with a zero vertical velocity. The uranium 238 ions, having a slower horizontal velocity than the uranium 235 ions, will require slightly more than a complete cycle to pass through plates 3, 3 and will emerge therefrom with a small vertical velocity. This vertical velocity will vary sinusoidally for successive 238 ions depending upon the time of their entry into the electrostatic field between plates 3, 3. Hence, the 238 ion beam will oscillate vertically about the 235 ion beam.

The horizontal velocity of the ion beams may be reduced by some factor, say 10, upon reaching the decelerating electrode 5, by adjusting its potential to the desired value, in order to accentuate the effect of the vertical velocity of the 238 ions. The ions are allowed to drift in space 6 until the desired separation is had. By the use of such decelerating electrode the space required for vertical separation is greatly reduced and the size of the equipment is brought within reasonable limits.

Under the above conditions, using the indicated voltages and frequencies, lengths of plates 3, 3 equal to 2.5 centimeters, with 1 centimeter separation between plates, and a drift distance 6 of 90 centimeters, the maximum vertical displacement of the 238 ion beam from the 235 ion beam in one direction at the collector is about 6 centimeters. If desired, the 235 ion beam could be accelerated again and passed through a second stage. It will be understood that the use of a single pair of plates of sufficient length to cover a whole cycle is only one embodiment of my invention, and that a pair of spaced plates which will only cover symmetrical or corresponding but opposite portions of the cycle would also be effective for the purpose.

In the embodiment of Fig. 1 complete separation of the isotopes cannot be obtained because of the necessity for the 238 ion beam to sweep across the 235 ion collector 8. Although the resulting contamination would likely be extremely small, it could be entirely eliminated by the alternating current plate arrangement shown in Figs. 2 and 3.

In that modification, transformers 11', 12' are of the center tapped secondary type similar to the one employed in Fig. 1. These transformers are fed by alternating current sources of any suitable type so that they deliver voltages to plates 13', 13' and 14', 14' which are 90° out of phase with each other. It will be seen from Figs. 2 and 3 that plates 14', 14' lie in spaced vertical planes while plates 13', 13' lie in spaced horizontal planes. Under these conditions the 238 ion beam, instead of oscillating will now rotate about a circle which will have a radius of about 6 centimeters at the collector since a rotating electrostatic field will be set up by the alternating current potentials impressed upon plates 13', 13' and 14', 14'. A circular collector or receiver 16' may be employed to collect the uranium 238 isotope. In this arrangement the uranium 235 isotope may be collected in receiver 8'.

From the foregoing it will become apparent that instead of employing the central collector 8 for the desired or chosen isotope, it may be desirable, particularly with elements of low mass numbers, to pass the undesired, or unchosen, isotopes through axially without appreciable deflection, and deflect the desired or chosen iso-

topes, collecting them in circular collectors, or measuring them as a direct current by simply permitting the ion beam to strike collectors or rings. This latter procedure is particularly well suited to elements having low mass numbers since the ions, being light, are more readily deflected sufficiently for separation purposes. In this connection, it should be stated that the deceleration introduced by electrode 5 is provided solely for the purpose of increasing the deflection, and may not be necessary in all cases. Where sufficient deflection can be obtained without recourse to this deceleration, electrode 5 could and should be omitted without in any way adversely affecting the operation. Of course, if the decelerating electrode 5 were omitted, screen 1, and the various collectors should be grounded.

In the modification of Fig. 4 sectors 15'', 15'' and 16'', 16'' are employed to replace the collectors, such as 16' of Fig. 3. As the ion beams rotate in conformity with rotating electrostatic fields set up by the plates, they pass from one of the pairs of sectors 15'', 15'' or 16'', 16'' to the other. The currents thus produced are led through leads 22'', 22'' to the resonant circuit including capacitance 19'' and inductance in the form of the primary of transformer 18'', and through leads 23'', 23'' to the resonant circuit including capacitance 21'' and inductance in the form of the primary of transformer 20''. The secondaries of these transformers feed alternating current measuring equipment. Thus with the split circular rings or collectors, the ion currents may be measured as an alternating current by feeding the pulses into resonant tank circuits. This is advantageous in that alternating current can be more easily amplified and measured than direct current.

In the foregoing arrangements, although the 235 ions will emerge from the electrostatic field with zero vertical velocity, they will be vertically displaced slightly, the vertical displacement varying sinusoidally with time. For instance, in Fig. 1, the 235 ion beam will actually oscillate slightly about the straight line path shown. This "displacement" modulation will also be superimposed on the "velocity" modulation of the 238 ions. Its maximum computed value in both cases is about .5 centimeter for the previously given dimensions and voltages. This displacement modulation could be cancelled out if desired by employing a second set of plates 17'', 17'', axially displaced horizontally from the first set of plates 3'', 3'' as shown in Fig. 5. Each 235 ion will enter plates 17'', 17'' exactly one-half cycle later than it enters plates 3'', 3'' and will receive an equal and opposite displacement. The 235 ion beam will therefore emerge from plates 17'', 17'' with zero vertical velocity and zero vertical displacement. Each 238 ion, because of its slower horizontal velocity, will enter plates 17'', 17'' slightly more than one-half cycle later than it entered plates 3'', 3''; therefore, the vertical velocity and displacement modulation it receives in plates 3'', 3'' will not quite be equal to that received in plates 17'', 17''. Accordingly, the 238 ions will still emerge with a vertical velocity and displacement although both will be of a smaller magnitude than results from the arrangement of Fig. 1.

While the foregoing invention has been largely illustrated in connection with the separation of uranium isotopes, it will be understood that it may be employed for general isotope separation, whether the materials utilized are fissionable or

not. For example, the isotopes 63 and 65 of copper or the isotopes of any other element may be equally well separated by the foregoing arrangements.

Having thus described my invention, I claim:

5. An isotope separation system of the character described comprising an ion source for producing ions from neutral vapors, means for accelerating the ions into a transverse alternating electrostatic field for selectively deflecting ions of different masses, collectors for said ions spaced from said field, and means for decelerating the ions leaving said field for accentuating their deflection while travelling through the space to the collectors.
10. An isotope separation system of the character described comprising an ion source for producing ions from neutral vapors, a source of alternating potential and a pair of spaced electrodes for establishing a transverse electrostatic field for deflecting ions passing therethrough, accelerating electrodes positioned on either side of the field for ejecting the ions from the source and moving them through the field at a uniform velocity, a decelerating electrode for accentuating the deflection of the ions, and means spaced from the field for collecting and measuring said ions.
15. An isotope separation system of the character described comprising an ion source for producing ions from neutral vapors, means for establishing a transverse alternating electrostatic field spaced from the ion source, accelerating electrodes positioned on either side of said field for ejecting the ions from the source and moving them into the field at substantially right angles thereto, said field being synchronized with the movement of the ions of a predetermined isotope for deflecting the ions of other isotopes passing therethrough into separate paths, a decelerating electrode for accentuating the deflection of the ions, and means spaced from the field and in the paths of said ions for measuring the ions so separated.
20. An isotope separation system of the character described comprising an ion source for producing ions from neutral vapors, a transverse rotating electrostatic field, means for applying an accelerating potential to said ions for causing them to pass therethrough, said field deflecting the ions of respective isotopes into respective paths which periodically describe circles, and circular collectors positioned in the paths of travel of said ions for collecting them.
25. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
30. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
35. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
40. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
45. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
50. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
55. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
60. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
65. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
70. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.
75. An isotope separation system of the character described comprising an ion source for producing ions from neutral vapors, a transverse rotating electrostatic field, means for subjecting the ions to an accelerating potential for moving them into said field, said field being synchronized with the movement of the ions of a predetermined isotope for deflecting the ions of other isotopes into paths which periodically describe circles, and circular shaped collecting means positioned in the paths of travel of the ions for collecting them and measuring the resulting current therefrom.

7
ions to the action of a decelerating potential to accentuate their deflection, and means for collecting said ions.

7. An isotope separation system of the character described comprising an ion source for producing ions from neutral vapors, a transverse rotating electrostatic field spaced from the ion source, accelerating electrodes positioned on either side of the field for ejecting ions from the source and causing them to move through the field, said field being synchronized with the movement of the ions of a predetermined isotope for deflecting the ions of other isotopes into paths which periodically describe circles, means for applying a decelerating potential to the ions after they leave the field to accentuate the deflection, and concentric circular collectors spaced from the field for collecting the ions.

8. An isotope separation system of the character described comprising an ion source for converting neutral vapors into ions, means for accelerating the ions into a transverse rotating electrostatic field, said field deflecting the ions of the respective isotopes into respective paths which periodically describe circles, and a plurality of sectors defining a series of broken concentric

circles spaced from the field for producing a pulsating ion current corresponding to the number of ions of the respective isotopes striking them.

9. An isotope separation system of the character described comprising an ion source for producing ions from neutral vapors, spaced sets of opposed plates for setting up alternating electrostatic fields, means for accelerating said ions between said plates, said plates being so positioned and the fields thereof being so synchronized with the movement of the ions of a predetermined isotope that such ions leave the field without appreciable deflection while ions of other isotopes are deflected into separate paths, means for decelerating said ions after they pass through said plates and means spaced from the field for collecting the ions leaving the field.
